ATTORNEY

UNITED STATES PATENT OFFICE.

DARBY L. BAKER, OF ATLANTA, GEORGIA.

SEMIMECHANICAL PHOSPHATE DEN.

Application filed July 30, 1928. Serial No. 296,402.

This invention relates to a phosphate den, the general object of the invention being to provide a device which can be constructed and operated at low cost and the operation 5 of which is continuous, as there are no interruptions for charging and discharging, and one in which the operators are protected from the fumes.

Another object of the invention is to provide 10 a housing movable about its vertical axis and divided into a plurality of chambers, with means for charging one chamber while another chamber is being emptied, with a single means for charging the chambers 15 in succession and a single flue for drawing off the fumes from the chambers and from the charging device, with means for facilitating the removal of the material from the chambers without the operator entering 20 the chamber.

This invention also consists in certain other features of construction and in the combination and arrangement of the several parts, to be hereinafter fully described, illustrated 25 in the accompanying drawings and specifically pointed out in the appended claims.

In describing my invention in detail, reference will be had to the accompanying drawings wherein like characters denote like or corresponding parts throughout the several views, and in which:—

Figure 1 is an elevation, with parts in section, of the invention.

Figure 2 is a vertical sectional view through the housing of the device.

Figure 3 is a horizontal sectional view through Figure 2.

Figure 4 is a view of the base on which 40 the tracks are located which are engaged by the wheels on the bottom of the housing.

In these drawings, the numeral 1 indicates a base which forms a support for a pair of circular tracks 2, and 3 indicates the 45 housing which has the wheels 4 on its bottom which engage the tracks so that the housing can be revolved about its vertical axis. The housing is preferably of rectangular shape in cross section and it is divided 50 into four chambers by the diagonally arranged partitions 5 so that each chamber is of triangular shape in cross section, with

the base of the triangle at the side of the housing. Each chamber is also provided with a sloping bottom 6 which slopes downwardly to the side of the housing and each side of the chamber is formed with two pairs of door openings 7, one pair communicating with the lower part of each chamber and the upper pair with the upper part of each chamber. These openings are closed by the hinged doors 8 which are held in closed position by the bars 9 engaging the keeper members 10 at the sides of the door openings. As shown in Figures 2 and 3, the sloping bottom 6 of each chamber tends to cause the material in the chamber to gravitate toward the lower doors. Flanged openings 11 are formed in the top of the housing, one for each chamber, and a mixing pan 12 is supported on the floor 13 above the housing, with its spout 14 depending through an opening in the floor, the parts being so arranged that as the housing is rotated, the flanged openings will come under the spout 15 in succession so that the material in the pan can drop through each opening into the chamber below.

The numeral 15 indicates a part of the dust weighing hopper for introducing the finely ground phosphate into the mixing pan and the numeral 16 indicates a part of the acid measuring device for introducing the acid into the pan.

The numeral 17 indicates a flue for conveying the fumes and gases to the usual scrubber through the use of a suction fan, the lower part of this flue extending through an opening in the floor 13 and having a flaring end under which the flanged openings 11 will come in succession as the device is rotated so that the fumes and gases from the chambers will be drawn through this flue. A pipe 18 connects the flue with the spout 14 of the mixing pan and a pipe 19 connects the mixing pan with the flue. A pipe 20, having a flaring lower end, is connected with the flue 17 with its lower end adapted to cover the flanged opening 11 of that chamber which has been filled from the mixing pan, but has not reached the discharging position. As will be seen, the flue 17 is so arranged with respect to the spout 14 of the mixing pan that each chamber must make a half

revolution in order to pass from the charging position, where its opening 11 is under the spout, to the discharging position, where its opening 11 is under the flue.

5 The numeral 21 indicates the usual bucket elevator for receiving the treated material from the housing and conveying it to an overhead car, the housing for this elevator being shown at 22, and said housing is provided with a hopper 23 which receives the 10 material from the chambers of the housing and delivers it to the buckets of the conveyor.

15 A platform 24 is attached to the front part of the housing 22 over the hopper 23 so that a workman can stand on this platform and remove the material from the chamber to be discharged, after he has opened the lower doors of said chamber. A 20 platform 25 extends around the central portion of the housing so that an operator can stand thereon and loosen the material in the upper part of the chamber being discharged by opening the upper doors of said chamber.

25 From the foregoing it will be seen that when the device is in operation, the housing is turned to bring the opening 11 of the first chamber under the spout 14 of the mixing pan, so that the materials from the pan can be discharged into the said chamber. After 30 this chamber is filled, the housing is moved a quarter turn so as to bring the second chamber under the spout so that said chamber can be filled. While the second chamber is being filled, the first chamber has its opening 11 under the pipe 20 so that the fumes from this chamber will be carried off through the flue 17 and the gases and fumes 35 in the mixing pan and spout will be discharging through the pipes 18 and 19 into the flue. Then the housing is given another quarter turn which will bring the third chamber under the spout of the mixing pan 40 and the first chamber will be moved into discharging position with its opening 11 under the flue 17 and its door openings will be arranged over the hopper 23. As the 45 third chamber is being charged, the first chamber is being discharged by the operator opening the doors and pulling the material 50 from the chamber so that it will drop into the hopper 23 and thus be elevated by the buckets of the elevator 21.

55 It will be seen that the operation is continuous and that the phosphate remains in each chamber a predetermined time, according to the capacity of the apparatus and the tonnage desired to be manufactured. The 60 workman digging the material from each chamber, is always on the outside so that he is not exposed to the heat and fumes and the fumes and gases are carried off from the chambers and from the mixing 65 pan. The apparatus is compact and the

handling of the materials in charging and discharging the chambers is such as to insure the minimum cost of production and an improved product. It will, of course, be understood that the chambers may be 70 formed in other shapes and the housing may be divided into as many chambers as desired.

What I claim is:—

1. A device of the class described comprising a housing rotatably supported so that it can be moved about its vertical axis, means for dividing the housing into a number of chambers, each chamber having a filling opening at its top, means for filling 80 each chamber as the housing is rotated to bring the filling opening of each chamber under the filling means, means for drawing off fumes and gases from the chambers and from the filling means, each chamber having discharge openings in its sides, doors for closing the same, platforms arranged adjacent the door openings whereby a workman can draw the material from each chamber without entering the chamber. 90

2. A device of the class described comprising a housing rotatably supported so that it can be moved about its vertical axis, means for dividing the housing into a number of chambers, each chamber having a filling opening at its top, means for filling 95 each chamber as the housing is rotated to bring the filling opening of each chamber under the filling means, means for drawing off fumes and gases from the chambers and from the filling means, each chamber having discharge openings in its sides, doors for closing the same, platforms arranged adjacent the door openings whereby a workman can draw the material from each chamber 100 without entering the chamber and a conveyor for receiving the material discharged from the chambers, said conveyor being arranged at that side of the housing which is opposite the filling means so that the housing must be moved a half revolution to place the filled chamber in discharging position. 110

3. An apparatus of the class described comprising a base, a circular track thereon, 115 a housing, wheels on the bottom of the same engaging the track, partitions in the housing dividing the same into a plurality of chambers, each chamber having a sloping bottom which slopes downwardly and outwardly to the outer side of the chamber, upper and lower doors in each side of the housing, the housing having flanged openings in its top, one for each chamber, a mixing pan supported above the housing with its discharge spout arranged to discharge into each chamber through the filling opening thereof when the housing is rotated to place the chamber under the spout, a flue supported above the housing opposite the 120 125 130

mixing pan for receiving fumes from each chamber after the housing has been moved a half turn from the filling position, a pipe connecting the flue with the mixing pan, a pipe connecting the flue with the filling opening of the chamber which has been moved a quarter turn from its filling position, platforms arranged exteriorly of the housing adjacent the doors thereof, a conveyor and a hopper associated with the conveyor and arranged to receive the material removed through the door openings of the chamber which is in discharging position.

10 DARBY L. BAKER.
